(57) **CLAIM**

The ornamental design for a heel protector as shown and described.

DESCRIPTION

FIG. 1 is a top perspective view of a first embodiment of a heel protector, showing our new design.

FIG. 2 is a bottom perspective view thereof.

FIG. 3 is a front elevational view thereof.

FIG. 4 is a left elevational view thereof.

FIG. 5 is a right side elevational view thereof.

FIG. 6 is a right side elevational view thereof.

FIG. 7 is a top plan view thereof.

FIG. 8 is a bottom plan view thereof.

FIG. 9 is a top perspective view of another embodiment of a heel protector, showing our new design.

FIG. 10 is a bottom perspective view thereof.

FIG. 11 is a front elevational view thereof.

FIG. 12 is a rear elevational view thereof.

FIG. 13 is a right side elevational view thereof.

FIG. 14 is a left side elevational view thereof.

FIG. 15 is a top plan view thereof; and,

FIG. 16 is a bottom plan view thereof.

The broken lines showing certain surface features depict portions of the heel protector that forms no part of the claimed design.

1 Claim, 16 Drawing Sheets
